UNITED STATES PATENT OFFICE.

HEINRICH KOPPERS, OF ESSEN-RUHR, GERMANY, ASSIGNOR TO THE KOPPERS DEVELOPMENT CORPORATION, OF PITTSBURGH, PENNSYLVANIA, A CORPORATION OF PENNSYLVANIA.

APPARATUS AND PROCESS FOR BURNING CERAMICS AND THE LIKE.

Application filed August 31, 1921, Serial No. 497,367, and in Germany August 21, 1919.

(GRANTED UNDER THE PROVISIONS OF THE ACT OF MARCH 3, 1921, 41 STAT. L., 1313.)

This invention relates to annular ovens for burning ceramic goods, lime, dolomite and the like.

The guiding idea of the annular oven is based on the fact that in the individual compartments assembled in annular operation the air necessary for combustion passes over the material already burnt, thus cools the same and is itself preheated, in order to burn up with the solid or gaseous fuel introduced into the respective combustion chambers; the gases thus burnt pass from the combustion chamber over the still fresh or "green" material to yield to the latter their surplus heat and thus gradually heat the same. The carrying out of this principle, however, is opposed by practical difficulties inasmuch as, in the absence of any compulsory guidance inside of the annular oven, the air and waste gases do not take the paths which would correspond with the fulfillment of this task, but whirlpool formations, due to their buoyancy, take place which, on the one hand, result in making the preheating and cooling zones or times unduly long and, on the other hand, strongly jeopardize the cooling and preheating effect. Due to their buoyancy, the gases roll along on the ceiling, while from below the colder gases flow in the opposite direction and mix with the hotter ones and thereby cool the latter. Particularly are the lower strata of the burning oven or kiln heated to a lesser extent than the upper ones, and the burning process takes place under serious heat losses. The extension or prolongation of the cooling zone causes the oven to become extraordinarily large for a relatively small capacity without there being obtained, in spite of this fact, a cooling effect. The necessity still prevails of opening the filler openings at the ceiling for purposes of better cooling in order to let fresh air enter through these openings, so that the workers can get at the material burnt. This, however, results in the disadvantage for the burning zone that the air arrives there at a reduced temperature.

According to the invention, the guiding idea of the annular oven operation is to be rendered capable of being carried out in a practical manner by giving to the air or the

gases such compulsory paths as enable them to fully accomplish the several tasks assigned to them at any time. For that purpose the annular oven is divided into individual chambers by means of partitions, and definite paths are prescribed to the cooling air as well as to the burning gases and the waste heat. According to the rules of firing technology, the cooling air which is to become preheated by the hot material already burnt, is introduced into the oven at the bottom and drawn off at the top. Through a special by-pass channel in the partition of the burning chamber the highly preheated air is led, at the bottom of the chamber, to the gas supplied here through a special channel, in order to burn upwardly in the combustion chamber kept free by the mode of stacking the material to be burnt. The flame which is thus formed passes again, with even distribution throughout the material to be burnt, downward according to the rule that hot gases which are themselves to cool down, and heat things, must always flow from top to bottom. The waste heat from the burning chamber proper is then transferred directly into the neighboring chamber in which the fresh material to be preheated is placed, and also ascends here in the combustion shaft again to drop downward over the material from top to bottom. According to the stage at which the individual chambers find themselves in the annular operation, the different closures for permitting air and gas to flow to the different chambers are then either opened or closed.

In order to make the invention more clearly understood there are shown in the accompanying drawing means for carrying the same into practical effect, without limiting the invention to the details, which are illustrative and can be varied without departing from the invention.

In said drawing—

Figure 1 is a diagrammatical longitudinal vertical section of an oven illustrating and embodying the invention.

Fig. 2 is a vertical cross section on line II-II of Fig. 1.

Referring to the drawings, 10 is the channel of the annular oven proper and is sub-

divided, by partitions 11, into individual chambers which, according to the operation of the annular oven, alternately act as cooling, burning and preheating chambers. In the chambers *a* acting for the time being for cooling, the outside air is introduced through openings 12, especially exposed for this purpose, at the bottom of the chamber 10 and, while being preheated by the freshly burnt material, flows upward through the latter in uniform distribution. A channel 13 provided at each partition 11 and capable of being opened or closed by a slide 14, enables the highly heated air which comes out of the series of cooling chambers connected with each other, to pass into the chamber *b* then functioning as a burning chamber, and to go to the bottom of the same where it burns up with the gas introduced at this place through the channel 15. In the combustion chamber 17, which is kept free by the manner of stacking therein the material to be burnt 16, which is placed in the kiln through doorways in the sides or top of the chambers or in any other suitable manner, the flame develops which then leaps beyond the material to enter the next chamber *c* through the channel 18 under the partition 11. The slide 14 on the channel 13 is closed as well as in all following chambers.

In order to prevent the direct passage of the gases from the cooling chambers into the burning chamber, the channel 18, by means of perforations 19 in the partition 11, is filled with sand (illustrated at right hand end of Fig. 1), so that in this manner a simple closing device or seal which can be depended upon at the high temperatures is created. This sand, whenever the chambers are freshly charged, is cleaned out and the passage 18 thus opened, while the transition or change of a preheating chamber to a burning chamber is always brought about again by filling the perforations with sand. The waste heat flowing into the preheating chambers *c*, again in the first place goes upward through the chamber 17 and is distributed above the material throughout the same to be drawn downward again and finally pass from the last preheating chamber through closure 20 which is open here, into the chimney, as seen at the right hand of Fig. 1.

In heating such kilns with gas, as is well known, one part of the air required for the complete oxidation of the fuel, about one half, reaches the oven as low pressure air in the gas, so that the quantity added as cooling air, as compared with the operation of such an oven by stoking with solid fuel becomes too large. Now in order to avoid the detrimental effect this would have on uniform combustion, it is advisable at the transition point from cooling to burning chamber, to draw off to the outside from the

former chamber *a* through openings 21 a suitable part of the air. So that the sensible heat of this quantity of air, however, may again be properly utilized for the burning operation, this quantity of air flows through a heat interchanging device 22 in the shape of a one- or two-chamber heater by which the gas supplied from conduit 23, for instance specially cooled previously with a view to perfect cleaning, can be preheated. In this way, the detrimental effect of surplus air on a practically perfect combustion is avoided but at the same time the heat absorbed by the air and taken away from the material is led back into the combustion process to serve a useful purpose.

In burning lime and the like the mass remaining after the burning only amounts to a little more than one half, since 44 weight parts of CO_2 escape from 100 parts of CaCO_3 . If the firing is effected here by a special gas producer plant, the burnt material just suffices to preheat the low pressure air. From the burning chamber the 44 weight parts of carbonic acid escape in addition to the waste heat gases. Here the heat surplus available over and beyond the preheating of the "green" material can be drawn off, therefore, between the burning and preheating chambers and utilized on its part for preheating the material to be burnt. This case fundamentally corresponds to the above-mentioned example; only here the heat item available is taken away at another place.

With the arrangement described, the fundamental idea of the annular operation is therefore carried out in the most perfect manner, by affording the best conditions for each individual stage of the cooling, burning and heating, without there being any possibility of a disturbing reaction from one stage to another taking place. This results in a control of the operation as a whole which insures a much better utilization of the fuel necessary for burning, on the one hand, and of the burning space available in the annular oven on the other hand. The special form given to the arrangement in this connection proves particularly suitable, above everything else the closing of the seals located at the hottest place by means of the introduction of sand, although, of course, the use of valves to be operated in the annular oven from above is not precluded. For burning lime, dolomite, etc., the oven would receive a removable ceiling, so that the limestone can be poured in from above and the burnt lime also be withdrawn from above by means of a hoist.

What is claimed is—

1. An annular oven for burning ceramic ware and the like, in combination: a series of connected oven chambers adapted to be operated successively as cooling, burning and

preheating chambers; partitions separating said chambers; a plurality of passage openings in said partitions, one set in the upper portion of said partitions providing a communication from the upper part of one chamber to the lower part of the next adjacent chamber and the other set of passage openings located in the lower portion of the partitions and communicating with the lower part of the said next adjacent chamber, each of said passage openings adapted to be opened and closed; openings in the lower portions of said chambers for admission of cooling air; heat supply openings located in the lower part of the chambers adjacent said partitions; the passages in the upper part of said partition adapted to be opened and the passages in the lower part of said partitions adapted to be closed between the cooling and burning chambers; the upper passages adapted to be closed and the lower passages adapted to be opened between the burning and preheating chambers and between each preheating chamber.

2. An annular oven for burning ceramic ware and the like, in combination: a series of connected oven chambers adapted to be operated successively as cooling, burning and preheating chambers; partitions separating said chambers; a plurality of passage openings in said partitions, one set in the upper portion of said partitions providing a communication from the upper part of one chamber to the lower part of the next adjacent chamber, by-passes leading from the top of the oven to said passage openings to enable closing of said passage openings, and the other set of passage openings located in the lower portion of the partitions and communicating with the lower part of the next adjacent chamber, by-passes leading from the top of the oven to the lower passage openings adapted to be filled with sand to close said lower passage openings; openings in the lower portions of said chambers for admission of air for cooling; heat supply openings located in the lower part of the chambers adjacent said partitions; the passages in the upper part of said partitions adapted to be opened and the passages in the lower part of said partitions adapted to be closed between the cooling and burning chambers; the upper passages adapted to be closed and the lower passages opened between the burning and preheating chambers and between each preheating chamber.

3. A process for operating annular ovens having separating and communicating chambers consisting in constituting and operating said chambers successively as a cooling chamber, burning chamber and preheating chamber; drawing cooling air in through the lower portions of the cooling chamber; withdrawing to the outside of the oven a portion of the preheated air from such cooling chamber and drawing the remainder of such preheated cooling air off from the upper portions of said cooling chamber; and admitting such remaining preheated air into the lower portion of the burning chamber to support combustion in the lower portion thereof so that the flame and products of combustion will flow directly upwardly and then downwardly in said burning chamber; withdrawing such products of combustion off through the lower portion of the burning chamber and admitting them into the lower portion of the preheating chamber so that they flow directly upwardly, then downwardly therein and then into the lower part of the next preheating chamber, such products of combustion through the remainder of said preheating chambers in the same manner as they flow from the burning chamber through the first preheating chamber and withdrawing the products of combustion from the last preheating chamber.

4. A process of operating annular ovens having separating and communicating chambers consisting in constituting and operating said chambers successively as a cooling chamber, burning chamber and preheating chamber; drawing cooling air in through the lower portions of the cooling chamber; withdrawing to the outside of the oven a portion of the preheated air from such cooling chamber before the remainder of such preheated air reaches the burning chamber and passing such withdrawn portion through a heat recovery plant to impart heat to preheat gas for the burning chamber; drawing the remainder of such preheated cooling air off from the upper portion of the cooling chamber and admitting it into the lower portion of the burning chamber to support combustion therein in the lower portion thereof so that the flame and the products of combustion will flow directly upwardly and then flow downwardly; withdrawing such cooling air commingled with the products of combustion off through the lower portion of the burning chamber and admitting them into the lower portion of the preheating chamber so that they flow first upwardly and then downwardly; passing such products of combustion through the remainder of said preheating chambers in the same manner as they flow from the burning chamber through the first preheating chamber and withdrawing the products of combustion from the last preheating chamber.

5. A method for operating annular ovens having separated and communicating chambers, consisting in communicably connecting a plurality of chambers in series and constituting and operating each of the chambers in the series successively as a cooling chamber, a burning chamber and a pre-heating chamber, with suitable admission of air and preheated combustion gas, and with-

drawing surplus heated air from the cooling chamber, and preheating the said combustion gas for the burning chamber by means of said withdrawn surplus air.

- 5 6. An annular oven or kiln for burning ceramic ware and other substances, having, in combination, a series of connected oven chambers, and partitions separating said chambers; each oven chamber having a combustion gas supply opening, a fresh air supply opening into the bottom part of the chamber, a discharge opening from the top part of the chamber, a discharge opening to a draft device from the bottom part of the chamber, a communication from the top part of the chamber to the bottom part of the next chamber, and a communication from the bottom part of each chamber to the bottom part of the next chamber; means in each chamber for extending said communications from said bottom parts to the top of the chamber and separate means controllable from the outside for opening and closing all of said openings and communications; whereby each oven chamber can be made successively and for a time a cooling chamber, a burning chamber and a preheating chamber.
- 15 7. An annular oven or kiln for burning ceramic ware and other substances, having, in combination, a series of connected oven chambers, and partitions separating said chambers; each oven chamber having a combustion gas supply opening, a fresh air supply opening into the bottom part of the chamber, a discharge opening from the top part of the chamber, a discharge opening to a draft device from the bottom part of the chamber, a communication from the top part of the chamber to the bottom part of the next chamber, and a communication from the bottom part of each chamber to the bottom part of the next chamber; means in each chamber for extending said communications from said bottom parts to the top of the chamber and separate means controllable from the outside for opening and closing all of said openings and communications; whereby each oven chamber can be made successively and for a time a cooling chamber, a burning chamber and a preheating chamber.
- 20 8. An annular oven or kiln for burning ceramic ware and other substances, having, in combination, a series of connected oven chambers, and partitions separating said chambers; each oven chamber having heating means, a fresh air supply opening into the bottom part of the chamber, a discharge opening from the top part of the chamber, a discharge opening to a draft device from the bottom part of the chamber, a communication from the top part of the chamber to the bottom part of the next chamber, and a communication from the bottom part of each chamber to the bottom part of the next chamber; means in each chamber for extending said communications from said bottom parts to the top of the chamber and separate means controllable from the outside for opening and closing all of said openings and communications; whereby each oven chamber can be made successively and for a time a cooling chamber, a burning chamber and a preheating chamber; and means for preheating the combustion gas by the heated air discharged from the oven chambers; each of said oven chambers being further subdivided into a plurality of oven chambers.
- 25 9. An annular oven or kiln for burning ceramic ware and other substances, having, in combination, a series of connected oven chambers, and partitions separating said chambers; each oven chamber having a combustion gas supply opening, a fresh air supply opening into the bottom part of the chamber, a discharge opening from the top part of the chamber, a discharge opening to a draft device from the bottom part of the chamber, a communication from the top part of the chamber to the bottom part of the next chamber, and a communication from the bottom part of each chamber to the bottom part of the next chamber; means in each chamber for extending said communications from said bottom parts to the top of the chamber and separate means controllable from the outside for opening and closing all of said openings and communications; whereby each oven chamber can be made successively and for a time a cooling chamber, a burning chamber and a preheating chamber; and means for preheating the combustion gas by the heated air discharged from the oven chambers; each of said oven chambers being further subdivided into a plurality of oven chambers.

- 30 10. A process for operating annular ovens having separated and communicating chambers consisting in connecting a plurality of chambers in series and constituting and operating said chambers of the series successively as a cooling chamber, burning chamber and preheating chamber; drawing cooling air in through the lower portions of the cooling chamber; drawing such preheated cooling air off from the upper portion of the cooling chamber and admitting it into the burning chamber to support combustion therein so that the flame and products of combustion will flow upwardly and then downwardly therethrough; withdrawing the products of combustion off through the lower portion of the burning chamber and flowing them into the lower portion of the preheating chamber so that they flow upwardly and then downwardly therethrough; passing such products of combustion through the remainder of said preheating chambers in the same manner as they flow from the burning chamber through the first preheating chamber; withdrawing a portion of the heat sur-
- 35 40 45 50 55 60 65 70 75 80 85 90 95 100 105 110 115 120 125 130

part of the next chamber; means in each chamber for extending said communications from said bottom parts to the top of the chamber and separate means controllable from the outside for opening and closing all of said openings and communications; whereby each oven chamber can be made successively and for a time a cooling chamber, a burning chamber and a preheating chamber; and means for preheating the combustion gas by the heated air discharged from the oven chambers.

9. An annular oven or kiln for burning ceramic ware and other substances, having, in combination, a series of connected oven chambers, and partitions separating said chambers; each oven chamber having a combustion gas supply opening, a fresh air supply opening into the bottom part of the chamber, a discharge opening from the top part of the chamber, a discharge opening to a draft device from the bottom part of the chamber, a communication from the top part of the chamber to the bottom part of the next chamber, and a communication from the bottom part of each chamber to the bottom part of the next chamber; means in each chamber for extending said communications from said bottom parts to the top of the chamber and separate means controllable from the outside for opening and closing all of said openings and communications; whereby each oven chamber can be made successively and for a time a cooling chamber, a burning chamber and a preheating chamber.

10. A process for operating annular ovens having separated and communicating chambers consisting in connecting a plurality of chambers in series and constituting and operating said chambers of the series successively as a cooling chamber, burning chamber and preheating chamber; drawing cooling air in through the lower portions of the cooling chamber; drawing such preheated cooling air off from the upper portion of the cooling chamber and admitting it into the burning chamber to support combustion therein so that the flame and products of combustion will flow upwardly and then downwardly therethrough; withdrawing the products of combustion off through the lower portion of the burning chamber and flowing them into the lower portion of the preheating chamber so that they flow upwardly and then downwardly therethrough; passing such products of combustion through the remainder of said preheating chambers in the same manner as they flow from the burning chamber through the first preheating chamber; withdrawing a portion of the heat sur-

105 110 115 120 125 130

plus at a high temperature stage from between the burning and preheating chambers and subjecting such withdrawn heat to heat recovery and withdrawing the remainder of 5 such products of combustion from the last preheating chamber.

11. A method of operating annular ovens having separated and communicating chambers consisting in passing cooling air into 10 the lower portions of the cooling chamber

and upwardly through the previously burnt material therein, withdrawing preheated cooling air from the upper portions of said cooling chamber and passing such air from the upper portion of the cooling chamber ¹⁵ into the lower portion of a next adjacent burning chamber to support combustion there.
